UNITED STATES PATENT OFFICE.

LEWIS E. WATERMAN, OF ROCKFORD, ILLINOIS, ASSIGNOR TO EMERSON-BRANTINGHAM COMPANY, OF ROCKFORD, ILLINOIS, A CORPORATION OF ILLINOIS.

CULTIVATOR.

1,201,399.

Specification of Letters Patent. Patented Oct. 17, 1916.

Application filed February 3, 1912, Serial No. 675,385. Renewed September 21, 1914. Serial No. 862,789.

To all whom it may concern:

Be it known that I, LEWIS E. WATERMAN, a citizen of the United States, residing at Rockford, in the county of Winnebago and 5 the State of Illinois, have invented certain new and useful Improvements in Cultivators, of which the following is a specification.

This invention relates to cultivators and 10 has more particular reference to those in which the supporting-wheels and shovel-beams may be angled in unison with respect to the line of draft.

The cultivator of my present invention is 15 of the general type disclosed in my companion application Ser. No. 654,401, filed Oct. 12, 1911, which embodies a supporting-wheel and shovel-beam mounted on a crank-axle at each side of the frame in such manner 20 that each crank-axle might swing on a separate vertical axis to angle its wheel and beam with respect to the line of draft, and a parallelogram frame connected with each crank-axle for raising and lowering the 25 crank and its shovel-beam. The carrying-wheels are connected through a seat support, for maintaining the wheels in parallelism, the seat-support being movable laterally to angle the wheels in unison.

30 One of the primary objects of this invention is to provide a cultivator of the foregoing type with means for automatically locking the shovel-beams in their raised position.

35 Another important object of my invention is to provide means, preferably foot-operated, for releasing the shovel-beams from their locked position, which means are operable also for guiding the cultivator by 40 angling the wheels and beam with respect to the line of draft. My aim in regard to this feature is to provide commonly operated means for both moving the beams vertically and angling the wheels with respect 45 to the line of draft. Such means are provided so that when a driver has finished cultivating a row and is about to commence another one (the beams having been locked elevated at the end of the row), he may release the beams and move them into lowered 50 working position by mechanism which is also operable for guiding the cultivator by angling the wheels.

55 Another object is to provide foot-operated means for moving the beams vertically

and angling the wheels and to so associate these foot-operated means with the foot-operated means for releasing the beams from their raised locked position that the operation of raising and lowering the beams and 60 of guiding the cultivator will be easy to perform.

I also aim to provide means of a novel design for raising and lowering the cultivator-beams and for automatically locking 65 them raised, whereby a very serviceable and efficient structure which may be manufactured at a low cost results. I also embody in this means a foot operated latch for automatically engaging a beam-member when 70 the beam has been moved to a raised position to lock the beam therein, whereby the latch may be manually operated to release the beam.

Another feature of my invention is the 75 provision of a quadrilateral beam raising and lowering frame with sides of unequal lengths and arranged in such manner that the rear end of the beam carried by such frame may be raised higher than its forward end.

In the accompanying drawings: Figure 1 is a perspective view of a cultivator embodying my improvements, the near carrying wheel being removed, and the far beam being shown elevated. Fig. 2 is a side elevation of Fig. 1. Fig. 3 is a perspective view of the foot lever means for raising a beam, the beam shown locked in its elevated position. Fig. 4 is a plan view of the swinging 90 seat support. Fig. 5 is a plan section of the support latch taken on the line *a—a* of Fig. 2.

The frame of the cultivator comprises the tongue 1 connected to the diverging bars 2 95 which are connected by a cross bar 3. The diverging bars are connected with the cross bars by brackets 4 which are part of the vertically disposed tubular journal sections 8. A vertical shaft 7 is journaled in each 100 section 8 and carries at its lower end an axle 5 upon which is mounted a carrying wheel 6. Adjacent the lower ends of shafts 7 are bracket portions 10 fixedly attached to said shafts, and to the bracket portions 10 are 105 bolted rearwardly extending seat supporting bars 11. A cross bar 12 supporting seat 18 connects these bars 11 by a hinged joint 13 at one end of the bar 12, and a latch device at its other end, comprising, a yoke 14 110

bolted to the bar 11 and having a vertical cross-pin 15, and a bracket 16 which supports a pivoted spring actuated catch 17 that is adapted to engage the cross-pin 15 and thereby lock the latch device; this seat support and latch device forming the subject matter of a divisional application of this case and bearing Patent Number 1,064,267, dated June 10, 1913. It will be noted that while the cross bar 12 forms a seat support which can be swung open to allow the driver to enter in front of the seat, it also forms the connection between the two shafts 7, and thus between the supporting wheels 6 whereby both wheels when angled to the line of draft through the pivoting of shaft 7, will angle simultaneously.

A toothed-segment 9 is bolted to the upper end of each shaft 7 and a hand lever 19 pivoted to each toothed-segment, is provided with the usual manually operable latch, and has a forward extension 20, providing a bell-crank arm, which supports a roller 21.

To each of the toothed-segments 9 is pivoted a link 22 which rests upon a roller 21. The inner end of each axle 5 is provided with a forwardly extending crank arm 23 shorter than the link 22 and having its end turned inwardly as indicated by 24 and disposed parallel with axles 5 and forming a Z-shaped member. And bar 27 shorter in length than the distance between the pivot of axle 5 and link 22 is pivotally connected at its ends to each of the links 22 and axle 35 crank sections 24, this latter connection being by brackets 26 which are bolted to the bars 27 and have externally square sleeve extensions 25 loosely mounted on the sections 24, there being fingers 28 bolted to the outer sides of bars 27 and overhanging the crank arms 23 to hold the bars and sleeves in position. It will be noticed that the above structure forms a quadrilateral frame the opposed sides of which are unequal in length. This frame which is a beam supporting frame has the general character of a parallel movement structure, whereby the bar 27 will be bodily elevated; but by reason of the unequal lengths of the opposite sides 50 of the frame, said bar 27 will be canted to an angled position to raise angularly a beam carried by said frame. A beam 29 or beam supporting frame is attached to the lower end of each bracket 26, substantially at right angles to bar 27, and forms a support to which shovels 30 or various other earth agitating devices may be attached. Inset shovels 31 are supported through the sleeves 25. Draft means are attached to the forward 60 end of the beams 29 and have connection with the tongue 1.

To each bracket 10 is pivoted a yoke 32 having at its forward end a slot 33 through which a bolt 34 passes and connects the yoke with the bar 27, and to each yoke is

connected a foot-lever 38 by which means the yoke is rocked to raise the bar 27 and beam 29. A bell-crank lever having on one arm a foot-lever 35 and on its other arm a catch 36, is pivoted to each yoke 32 and a spring 37 has one end fastened to the catch and its other end to the bar 11, to hold the catch forward yieldingly.

With the operable parts of the cultivator in a position as shown in Fig. 2, to raise a beam to an elevated position two methods are possible, one by means of a foot-lever and the other by means of a hand-lever. By the first method the driver presses downward on foot-lever 38, thereby rocking the yoke 32 and raising in a swinging parallel like movement the bar 27, thereby raising the beam 29. Since the bar 27 forms a side of a quadrilateral and is shorter than its opposite side, (the shaft 7) it will not assume a vertical position throughout its raising, but will be canted to an angle as is shown in the raised position of Fig. 1, thus raising the beam 29 in an angled position with the rear end thereof higher from the ground than the front end. Inclination of the beam is desirable when traveling with the beam elevated, for the reason that rocking of the beam results by the rising and falling movement of the tongue 1 caused by the horses and by passing over uneven ground, and therefore this higher elevated position of the rear shovels gives them a wider range of rise and fall without contacting with the ground. The forward shovels are not required to be subject to such diversity of movement. When the beam has reached its said elevated position the catch 36 will engage an under face of sleeve 25 as shown in Fig. 3, and thus hold the beam locked in its elevated position. To release the catch and drop the beam the driver presses downward on the foot-lever 35, thus disengaging catch 36 against the action of spring 37 and allowing the beam to fall. When it is desired to raise the beam by the second method, by hand, the lever 19 is moved backward and downward thereby raising the bar 27 through the arm 20 roller 21, and the catch 36 locking the beam when in its raised position, as above described.

It will be noticed that at any time the lever 19 can be operated to regulate the depth to which the shovels shall work, through means of the arm 20 and roller 21, and that by setting the lever in a position for the desired working depth, the foot-lever 38 can be operated entirely to raise the beam. When the beam is lowered the link 22 will be limited in its downward movement by the set roller 21, whereby the shovels will be limited in their working depth.

When cultivating it is desirable that the driver have his hands free from operating any of the shovel mechanism in order that

he may properly handle the reins to guide the team. It is necessary to raise and lower the shovels because of obstructions and at the end of a row when turning around; also 5 it is necessary to guide or steer the cultivator independent of the guiding by the horses, which is done by angling the wheels and beams by swinging them horizontally on their pivotal supports on the shafts 7. 10 These desirable and necessary operations in efficient cultivating are attainable by my improved cultivator, for it will be seen that in driving along in operation, (the beams lowered) the driver may raise the beams by 15 the foot-levers, his hands being free to handle the team, and when he turns at the end of a row, (the beams now elevated) by pressing down on each catch release foot-lever 35 he may lower the beams, the beams 20 dropping to their predetermined depth limited by the hand levers 19. Now it becomes immediately necessary that the cultivator be properly guided, and with his feet still upon the catch release levers 35 25 he may control positively, by forward pressure on these levers, the angling of the carrying wheels in whatsoever direction he desires, the shovels being not affected in their working position other than being angled 30 laterally in unison.

From the foregoing it will be manifest that I have provided novel means for controlling the raising and lowering of the shovel-beams and for guiding the cultivator 35 by angling the wheels with respect to the line of draft, and that the same are arranged for most convenient operation by the driver, who may adjust or shift the beams easily and with little effort. 40 It is believed that my invention and its mode of operation will be fully understood from the foregoing and it will be obvious that the invention is not circumscribed by the details disclosed for purposes of illustration, and that the invention is capable of 45 adaption to various changes in construction without departing from the spirit of the invention as described in the appended claims.

I claim as my invention—

50 1. In a cultivator, the combination of a frame, wheels supporting the frame, two shovel supporting beams, a bar connected to each beam and extending substantially vertically, and two links connecting the bar with the frame, the upper link being longer than the lower link.

55 2. In a cultivator, the combination of a frame, wheels supporting the frame, two shovel supporting beams, a vertically disposed bar connected to each beam, two links connecting said bar and the frame, the links being of unequal length, and means for raising one of the links or said bar.

60 3. In a cultivator, the combination of a frame, wheels supporting the frame, two

shovel supporting beams, a vertically disposed bar connected to each beam, an upper and lower link connecting said bar with the frame, the distance between the connections of said links on the bar and the said links 70 on the frame being unequal, and means for raising one of the links on said bar.

4. In a cultivator, the combination of a frame, two vertically movable frames carried thereby and capable of horizontal pivotal movement, a supporting wheel connected to each frame, a shovel supporting beam carried by each of the movable frames, means for raising said frames, and a catch for each frame for holding its frame in a 75 raised position, the control for the catches forming means by which the movable frames 80 may be pivoted horizontally.

5. In a cultivator, the combination of a frame, two vertically movable frames carried thereby and capable of horizontal pivotal movement, a supporting wheel connected to each frame, a shovel supporting beam carried by each of the movable frames, means for raising said frames, and a foot 85 operated catch for each frame for holding its frame in a raised position, the foot control of the catches forming means by which the movable frames may be pivoted horizontally. 90

6. In a cultivator, the combination of a frame, supporting wheels therefor, said wheels being capable of horizontal movement at an angle to the line of draft, shovel supporting beams carried by the frame and 100 being movable with the movement of the wheels, means for raising said beams, and a catch for holding each beam elevated, the control for the catch forming means by which said wheels and beams may be angled 105 with respect to the line of draft.

7. In a cultivator, the combination of a frame, wheels supporting the frame, two vertically movable supports carried by the frame, a shovel supporting beam carried by 110 each of said supports, a link connecting each movable support and the frame, foot levers for raising said links, and catches carried by the links for engaging the movable supports and holding them in an elevated position. 115

8. In a cultivator, the combination of a frame, wheels supporting the frame, two vertically movable supports carried by the frame, a shovel supporting beam carried by each support, a link connecting each movable support and the frame, foot levers for raising the movable supports to an elevated 120 position, and catches carried by the links for holding the movable supports in an elevated position. 125

9. In a cultivator, the combination of a frame, wheels supporting the frame, a vertically movable support carried by the frame, a shovel supporting beam carried by said support, a foot lever pivoted to the 130

- frame for raising said movable support, and a spring catch mounted on said foot lever for engaging said movable support and holding it in its raised position.
- 5 10. In a cultivator, the combination of a frame, wheels supporting the frame, a vertically movable support carried by the frame, a shovel supporting beam carried by said support, a foot lever pivoted to the frame 70 having connection with said movable support and adapted to raise the support to an elevated position, and a catch carried by said lever for engaging the movable support and holding it in its elevated position.
- 10 11. In a cultivator, the combination of a frame, wheels supporting the frame, a vertically movable support carried by the frame, a shovel supporting beam carried by said support, means for raising and lowering 75 said movable support, and a foot releasable catch for engaging the support when it has been raised to its elevated position.
- 15 12. In a cultivator, the combination of a frame, wheels supporting the frame, a vertically movable support carried by the frame, a shovel supporting beam carried by said support, a foot lever for raising said movable support, and a spring catch carried 80 by the foot lever in an inoperative position when said support is lowered and adapted to swing into engagement with said support upon the support being raised by said foot lever to an elevated position.
- 20 13. In a cultivator, the combination with 85 a vertically movable beam support and a supporting wheel having a connection therewith, the beam support and wheel being pivotal together about an upright axis, of a beam connected with the beam support, and foot-lever means for moving the beam support vertically, including a foot-lever movable to swing the beam support and wheel about said axis.
- 25 14. In a cultivator, the combination with 90 a vertically movable beam and a supporting wheel having a connection therewith, both the beam and wheel being movable together about a vertical axis, means for moving the beam to an elevated position, means for locking the beam in this elevated position, and a foot-lever for releasing the beam from said locked position, said foot-lever being movable to swing the beam and wheel horizontally about said axis.
- 30 15. In a cultivator, the combination with 95 a vertically movable beam and a supporting wheel, the supporting wheel being movable horizontally about a vertical axis, a foot-lever mechanism for moving the beam vertically, a connection between said mechanism and the supporting wheel, and a foot operated member included in said mechanism and being movable to swing the supporting wheel about said vertical axis.
- 35 16. In a cultivator, the combination with 100 a vertically movable beam and a supporting wheel, the supporting wheel being movable horizontally about a vertical axis, means for moving the beam to an elevated position, a latch for holding the beam locked in its elevated position, a foot-lever having a connection with the latch and adapted to release the beam from said locked position, and a connection between the foot-lever and supporting wheel whereby the supporting wheel may be swung horizontally about said axis by the foot-lever.
- 40 17. In a cultivator, the combination with 105 two vertically movable beams and two supporting wheels, each beam having a connection with a supporting wheel and each connected beam and wheel being movable horizontally about a vertical axis, of a connection between the connected beams and wheels whereby the both sets of beams and wheels may move horizontally together, and foot actuated means for actuating the beams in their vertical movement, said foot actuated means being movable to move the beams and 110 wheels horizontally.
- 45 18. In a cultivator, the combination with 115 two vertically movable beams and two supporting wheels, each beam having a connection with a supporting wheel and each connected beam and wheel being movable to a position angled to the line of draft, of a connection between the two sets of connected beams and wheels, and means for moving the beams vertically including a foot-lever adapted to be moved to angle the beams and 120 wheels to the line of draft.
- 50 19. In a cultivator, the combination with 125 a vertically movable beam and a supporting wheel having a connection therewith, the beam and wheel being movable together to a position angled to the line of draft, of means for raising the beam to an elevated position, means for locking the beam in this elevated position, and a foot-release for breaking said lock, said foot-release being movable to angle the beam and wheel to the line of draft.
- 55 20. In an earth agitating implement, the combination with a vertically movable beam member, of a pivoted foot-lever having a 130 connection with said member and adapted to raise the same to an elevated position, and a catch carried by said foot-lever and adapted to engage and lock in position the beam member when it has been raised to its said elevated position.
- 60 21. In an earth agitating implement, the combination with a vertically movable beam member, of a pivoted foot-lever having a 135 connection with said member and adapted to raise the same to an elevated position, a catch carried by said foot-lever and adapted to engage and lock in position the beam member when it has been raised to its said elevated position, and a foot-release con-

nected to said catch to allow the catch to be foot released from its said locked engagement.

22. In an earth agitating implement, the combination with a vertically movable beam member, of means for raising the beam member to an elevated position, a catch movable into engagement with said beam member when the same has been elevated, and a foot-operated member connected to said catch for releasing the catch from its said engagement with the beam member.

23. In an earth agitating implement, the combination with a vertically movable beam member, of means for raising the beam member to an elevated position, and a foot-lever having a member movable into engagement with the beam member to hold the same locked in its said elevated position.

24. In an earth agitating implement, the combination with a vertically movable beam member, of means for raising the beam member to an elevated position, and a foot-lever having a member movable into engagement with the beam member when the same has been raised to its elevated position for locking the beam member in such position, the foot-lever being operable to release its said member from said engagement with the beam member.

25. In an earth agitating device, the combination with a vertically movable beam member, of a pivoted foot-lever having a connection with said beam member and adapted to raise the same to an elevated position, and a second foot-lever pivoted to said foot-lever and having a latch member movable into a locked engagement with the beam member when the beam member has been elevated, said latch foot-lever being movable to release its latch from said engagement.

26. In a cultivator, the combination of a frame, a crank mounted thereon, a shovel-beam pivotally mounted on said crank, an upstanding arm fixedly connected to said beam adjacent to its pivot, a lever connected to said arm for moving the same vertically to raise and lower the crank and thereby the beam, and a catch carried by said lever for engaging a beam-connected portion when the beam has been moved to its elevated position.

27. In a cultivator, the combination of vertically movable shovel-beams, supporting-wheels movable about separate vertical axes, and a common means for automatically locking the beams in their raised position and for swinging the wheels about their axes.

28. In a cultivator, the combination of a frame, a wheel-support mounted at each side of the frame to turn on a vertical axis, a wheel mounted on each support, a cultivator-beam mounted on each support movable to

raised and lowered positions, a foot-lever 65 mounted on each support and connected with a cultivator-beam for moving the same vertically, means connecting the supports for holding the wheels and beams in parallelism, and means carried by the foot-levers for 70 automatically locking the beams in raised positions and for turning said supports to angle the wheels and beams with respect to the line of draft.

29. In a cultivator, the combination of a 75 frame, a supporting-wheel and a cultivator-beam mounted at each side of the frame to turn about a vertical axis, and foot-lever mechanism for raising and lowering each cultivator-beam, said mechanism being movable 80 with its beam about the vertical pivot axis thereof, and being operable to angle its beam and wheel with respect to the line of draft.

30. In a cultivator, the combination of a frame, a crank-axle at each side of the frame 85 mounted to oscillate about a vertical axis, a supporting-wheel mounted on each axle, a cultivator-beam mounted on each crank, a foot-lever connected with each crank for swinging the same vertically to raise and 90 lower the cultivator-beam, a foot-releasable catch mounted on each foot-lever for automatically locking the crank in its raised position, and means connecting the crank-axles for maintaining the wheels in parallelism. 95

31. In a cultivator, the combination of a frame, a crank mounted thereon, a shovel-beam pivotally mounted on the crank to be raised and lowered thereby, and means connected to the crank and beam and so controlling the movement of the latter that the beam will be in a practically horizontal plane when lowered and the rear end of the beam will be elevated higher than its forward end when the beam is raised. 100

32. In a cultivator, the combination of a frame, a crank mounted thereon, a shovel-beam pivotally mounted on the crank to be raised and lowered thereby, a vertically disposed arm fixedly connected to the beam at 110 the pivoted end thereof for holding the beam in a substantially horizontal position, means for swinging the crank to raise and lower the beam, and means for canting said arm during raising thereof to raise the rear end 115 of the beam higher than its forward end.

33. In a cultivating device, the combination of a frame, a pair of dirigible supporting-wheels therefor, a cultivating device associated with each wheel so as to be angled to 120 the line of draft therewith and be movable vertically with respect thereto, means for raising the cultivating devices and automatically locking them in raised positions, and means for releasing the cultivating devices 125 from said locked positions and for angling in unison the wheels and cultivating devices to the line of draft.

34. In a cultivator, the combination with
dirigible supporting-wheels and a cultivating
device associated with each wheel so as
to be angled to the line of draft therewith
5 and to be independently movable vertically
with respect thereto, means for independently
raising each cultivating device, a sepa-
rate foot-releasable means for automatic-
ally locking each cultivating device in
10 raised position and being operable for an-

gling in unison the wheels and cultivating
devices to the line of draft.

In testimony whereof I have hereunto set
my hand in presence of two subscribing wit-
nesses.

LEWIS E. WATERMAN.
